UNITED STATES PATENT OFFICE.

THOMAS J. GIBBONS, OF FARMINGTON, ILLINOIS.

CARPET-STRETCHER.

1,072,599.

Specification of Letters Patent.

Patented Sept. 9, 1913.

Application filed November 18, 1912. Serial No. 732,056.

To all whom it may concern:

Be it known that I, THOMAS J. GIBBONS, citizen of the United States, residing at Farmington, in the county of Fulton and State of Illinois, have invented certain new and useful Improvements in Carpet-Stretchers, of which the following is a specification, reference being had therein to the accompanying drawing.

10 This invention relates to carpet stretchers and has reference to a device which will hold the carpet in a stretched position while the same is being tacked to the floor.

Another object of this invention is the 15 production of a novel and efficient means for holding the stretcher bar in a central position upon a guiding bar while the carpet is being stretched.

With these and other objects in view this 20 invention consists of certain novel combinations, constructions, and arrangements of parts as will be hereinafter fully described and claimed.

In the accompanying drawings:—Figure 25 1 is a perspective view of the stretcher. Fig. 2 is a side elevation of a part of the operating mechanism showing a portion of the same in section. Fig. 3 is a perspective view of the attaching plate showing the stretcher bar in section. Fig. 4 is a top plan view of the attaching yoke which may be used in connection with this device showing the stretcher bar in section. Fig. 5 is a perspective view of the stop.

30 Referring to the accompanying drawing by numerals it will be seen that the device consists of a guiding bar 1 which carries at its inner end a block 2. Mounted upon the under side of the guiding bar 1 is an anchor- 35 ing member 3 which is provided with a prong 4 and head 5, whereby the same will be driven in the floor for preventing the stretcher from moving. The bar 1 and the block 2 are held together by means of the 40 bolts 6 which pass therethrough.

The block 2 is provided with a centrally located aperture 7 through which the shaft 8 passes. Mounted upon this shaft 8 are the ratchet wheels 9 which are held in place 45 by means of the screws 10. In order to operate the device there is provided an operating handle 11 which is provided upon its lower portion with a squared head 12. Mounted upon this squared head are the 50 plates 13, said plates 13 being adapted to straddle the block 2 and be carried by the

shaft 8 whereby the handle may be rocked when so desired. The handle 11 also carries the pawl member 14 which is adapted to engage the ratchet wheel 9 whereby the shaft 8 may be rotated.

60 Mounted upon the end portions of the shaft 8 are the detachable drums 15 which are held thereon by means of the screws 16. The drums 15 are adapted to hold the ropes 17 which are attached to the stretcher bar 18 by means of the attaching plates 19. The plates 19 are provided with a plurality of apertures 20 whereby the hooks 21 which are carried by the ropes 17 may be shifted when so desired. In order to hold the stretcher bar 18 in a central position relative to the guiding bar 1 there is provided a U-shape guiding member 22 which is held upon the stretcher bar 18 by means of the 70 rivets 23.

75 In order to allow the stretcher bar to engage the carpet there are provided a plurality of teeth 24 which are formed of U-shape strands of wire which pass through the stretcher bar and extend below the lower surface of the stretcher bar.

80 Fig. 4 of the accompanying drawings shows a modification that may be employed instead of the plate 19. This modification 85 comprises a single strand of wire or rod material bent into the form of a yoke 25, the legs 26 of which extend transversely through the bar 18. The yoke projects laterally from the forward longitudinal edge 90 of the bar 18, and the corners and central portion are coiled to provide the eyes 27, 28 and 29, adapted to be selectively engaged by the hooks 21. The legs of the yoke have their free ends 30 threaded for the reception 95 of the nuts 21 to lock the yoke to the bar 18. There is also provided a stop which is carried by the guiding bar 1 which is adapted to prevent the rope 17 from unwinding by preventing the ratchet wheel from moving 100 in one direction. This stop is formed from a single strand of wire and is formed to constitute an enlarged head 32 which terminates in the side arms 33, and the side arms 33 terminating in the eyes 30. When the 105 stop is mounted upon the wire it is held in the pivot position by means of the pivot member 35.

Having thus described the invention what is claimed as new, is:—

110 A carpet stretcher comprising a stationary central guide bar having an anchor at

one end, a supporting block attached to the bar adjacent the anchor, a shaft journaled in the block, drums carried by the ends of the shaft, ratchets mounted on the shaft on each side of the block, a lever pivotally mounted on the shaft and carrying pawls for engaging the ratchet, a pawl carried by the guide bar for engaging both ratchets to prevent reverse movement of the shaft, a

stretcher bar slidably mounted on the guide bar, and cable connections between the drums and the stretcher bar.

In testimony whereof I hereunto affix my signature in presence of two witnesses.

THOMAS J. GIBBONS.
